UNITED STATES PATENT OFFICE.

JOHN MAILER, OF SAN FRANCISCO, CALIFORNIA.

GRATE-BAR.

SPECIFICATION forming part of Letters Patent No. 292,837, dated January 22, 1884.

Application filed March 29, 1883. (No model.)

To all whom it may concern:

Be it known that I, JOHN MAILER, of San Francisco, in the county of San Francisco and State of California, have invented a new and useful Improvement in Grate-Bars, of which the following is a full, clear, and exact description.

Reference is to be had to the accompanying drawings, forming part of this specification, in which similar letters of reference indicate corresponding parts in all the figures.

Figures 1, 2, and 3 are respectively perspective and cross-sectional views of the grate-bars.

15 My invention relates to improvements in grate-bars; and it consists in the peculiar construction and arrangement of the parts, as hereinafter more fully set forth, and pointed out in the claims.

20 My improvements in the grate-bars of a furnace are clearly represented in the detail views of Figs. 1, 2, and 3, showing a double or cluster bar. I form each bar of a main plate, a^2 , tapered from top to bottom, as shown in Figs. 2

25 and 3, and widest at the center, as shown in Fig. 1, and form on the plates a^2 suitable spacing blocks or pieces, b^2 , for sidewise support of the bars, one by the other, by contact of the blocks b^2 ; and at each side and at the upper 30 edge of the plate a^2 , I form the fins or tongues c^2 , the tongues of one side being opposite the spaces between the tongues of the other side of the plate, or in transversely staggered position; and the tongues c^2 are beveled downward and inward to the plate a^2 , thus permitting, by their shape and relative position with each other, a very large and free air-inlet between the plates and tongues, while presenting ample surface for the support of very fine coal 35 or dust fires.

An important feature of my grate-bar is the concavity or groove in and along the top or fire surface of the bars, which may either be of rounded form, as at d^2 , Fig. 2, or of angular form, as at e^2 , Fig. 3, the object of the groove in either case being to form a receptacle along the top of the bar, in which ashes may lodge to protect the bar from the intense heat of the fire. The bars h may be connected by their 50 spacing-blocks b^2 , to form double or triple bars;

or be made singly, as indicated by the central vertical dotted line of Fig. 2.

A grate-bar thus constructed is cheaply made and readily applied to or removed from the furnace, and has in practice proved unusually durable and giving most satisfactory results.

I am aware that a grate-bar provided with a series of lugs or projections on its opposite sides, so arranged that the lugs on one bar will pass through the spaces between the lugs of the adjacent bars when the grate-bars are vibrated or rocked on their trunnions or journals, is old, and I therefore lay no claim to such invention. In my invention the grate-bars are fixed, and no vibration or rocking motion is imparted to them, and the tongues are arranged on both sides of the opposite plates of each bar in a staggered position, and beveled downward and inward to the plates a^2 , for the purpose of insuring a free and large air-inlet between the plates and tongues, and not to allow of the passage of the lugs by each other in the vibrations or rocking of the grate-bars in the constructions disclaimed.

Having thus described my invention, I claim as new and desire to secure by Letters Patent—

1. The fixed grate-bar composed of the parallel plates a^2 , provided with tongues c^2 on their opposite sides, beveled downward and inward to the plates, and arranged in staggered position, substantially as shown and described.

2. The combination, in a fixed grate-bar, of the plates a^2 , tongues c^2 , beveled downward and inward to the plates, and arranged in staggered position at opposite sides of the plates a^2 , and the parallel-edged spacing-blocks b^2 , substantially as shown and described.

3. The combination, in a fixed grate-bar, of the tapering plates a^2 , each having a recess along its upper edge, tongues c^2 , beveled downward and inward to the plates, and arranged in staggered position at opposite sides of the plates, and parallel-edged spacing-blocks b^2 , substantially as shown and described.

JOHN MAILER.
